Harvey M. Shellabarger

UNITED STATES PATENT OFFICE.

HARVEY M. SHELLABARGER, OF WAPELLO, IOWA.

MANUFACTURING OF FENCE-POSTS AND RAILROAD-TIES.

No. 840,263.

Specification of Letters Patent.

Patented Jan. 1, 1907.

Application filed December 5, 1905. Serial No. 290,494.

To all whom it may concern:

Be it known that I, HARVEY M. SHELLABARGER, a citizen of the United States, residing at Wapello, in the county of Louisa and State of Iowa, have invented a new and useful Process in the Manufacturing of Fence-Posts and Railroad-Ties, of which the following is a specification.

This invention has for its object the production of a fence-post and railroad-tie in which are combined all the advantages of a cement or stone post or tie and a wooden post or tie; and it consists of a wooden core and an inclosing envelop of cement or other plastic material.

This invention further consists of certain novel features of construction, all as herein-after shown and described, and specifically pointed out in the claim.

In the drawings illustrative of the invention, Figure 1 is a perspective view of the post complete. Fig. 2 represents a plain wooden core for the post. Fig. 3 represents a wooden core for the post partly wrapped with tar-paper. Fig. 4 is a cross-section of the tie and mold-box in which it is molded, and Fig. 5 is a perspective view of the tie.

C represents holes punctured through the cement or plastic-material casing of the post to allow staples or nails to be driven into the wooden core of the post.

A represents staples for fastening the running-wire to the post

B represents the nail for fastening the board or boards to the post.

D represents holes through the plastic material of the tie to enable spikes to be driven into the wooden core of tie.

E represents the spike.

The post and tie comprise wooden cores,

Figs. 4 and 9, entirely wrapped with tar-paper inclosed in a cement or other plastic-material envelop, thus having the appearance of a stone post or tie, nothing exposed in the finished post and tie, Figs. 1 and 6, but the 45 plastic material. The post or tie thus constructed possesses all the pressure-resisting and everlasting quality and power of a cement stone post or tie and all the transverse stiffness and breakage-resisting power 50 of the wooden post or tie. The post or tie will also be very durable and moisture-resisting. The post or tie may be of any size or length. The main thing to be considered is that the cores be large enough to stand the 55 strain which naturally comes on a post or tie.

My process of manufacturing said above post or tie is as follows: I first prepare or construct a wooden mold of various sizes to 60 accommodate the size of the post or tie desired; second, I prepare a wooden core of the size desired for either post or tie and wrap said wooden cores with tar-paper; third, I embed said wrapped wooden cores in 65 concrete or other plastic material; fourth, I puncture holes in said post or tie in order that staples, nails, or spikes may be driven into the wooden core of said post or tie.

Having thus described my invention, what 70 I claim is—

The process of forming a composite body consisting in wrapping a wooden core in tarred paper and permanently embedding the wrapped core in cement or other plastic material. 75

HARVEY M. SHELLABARGER.
